HENDERSON P. CHILDRESS, OF MEMPHIS, TENNESSEE.

BALE-BUCKLE.

1,366,357.

Specification of Letters Patent. Patented Jan. 25, 1921.

Application filed December 15, 1916. Serial No. 137,210.

To all whom it may concern:

Be it known that I, HENDERSON P. CHILDRESS, a citizen of the United States, residing at Memphis, in the county of Shelby and State of Tennessee, have invented a new and useful Bale-Buckle, of which the following is a specification.

This invention has reference to bale buckles, and its object is to provide a bale buckle of simple and efficient construction which may be made from heavy gage hard wire.

In accordance with the invention the buckle before being pulled is of approximately rectangular shape slightly narrower at the entering end than at the opposite end, and with the entering end formed of overlapping parts to be inclosed by the corresponding loop of the bale band with the parts brought into alinement from their normal overlapping relation by the pull exerted by the bale band under the expansive force of the bale. The construction is such that in the pulled buckle the two members of the entering end bar of the buckle have their meeting ends, which are beveled and initially overlapped, brought together, with the entering end of the buckle sufficiently spread to permit the alinement of the two parts of the entering bar, whereby the beveled ends are wholly housed within the corresponding loop of the bale band and the bale and adjacent objects are protected, while the loop of the band is firmly supported throughout its entire width, thus avoiding any tendency of tearing the band.

The inner corners of the buckle may be made substantially square or they may be rounded or beveled, in which latter case the pulled buckle tends to crimp the opposite edges of the band where it encircles the bars of the buckle, and thus resist any tendency of the band to render.

The invention will be best understood from a consideration of the following detailed description, taken in connection with the accompanying drawings forming part of this specification, with the further understanding that while the drawings show a practical form of the invention, the latter is not confined to any strict conformity with the showing of the drawings, but may be changed and modified so long as such changes and modifications come within the scope of the appended claims.

In the drawings:

Figure 1 is a face view of a buckle constructed in accordance with the invention, showing the buckle in its initial condition, that is, before being subjected to the pull of the bale band.

Fig. 2 is an edge view of the entering end of the buckle.

Fig. 3 is a view similar to Fig. 1 but showing a slightly different construction of the buckle and also showing the relative positions of the buckle and entering loop of the bale band before the buckle is pulled.

Fig. 4 is a view of the buckle of Fig. 3 after being pulled, and showing the entering loop of the bale band in cross-section.

Fig. 5 is a section on the line 5-5 of Fig. 4.

Fig. 6 is a view similar to Fig. 1 but showing a buckle made of flat metal.

Fig. 7 is a section on the line 7-7 of Fig. 6.

The several buckles shown in the drawing are illustrated approximately full size. Each buckle is made of a single piece of wire of heavy gage, say, No. 2 gage, and of a quality of wire known as hard wire, wherefore the buckle is capable of resisting heavy strains without bending materially from the initial condition.

The buckles shown in the drawings are in most part alike, differing only in certain details which will be specifically referred to, wherefore a general description of one buckle applies to all the buckles shown, and aside from the specific differences to be hereinafter described, the description of one buckle applies to all of them.

Each buckle comprises an end bar 1, two side bars 2, 3, and another end bar made up of two members 4, 5 constituting projections of the end bars 2 and 3, respectively. The buckle is approximately rectangular, and it may with advantage be made somewhat wider than long, the length of the buckle being measured with respect to the distance from one end bar to the other, including the end bars, while the width is measured with respect to the distance from one side bar to the other including the side bars. Expressions of position have to do with the buckle as applied to a bale, and in such case the usual position is that the end bar 1 is uppermost, the buckle being applied to one end of the bale band at the bench with such end of the bale band at the bench with such

end encircling the bar 1, and the buckle hangs pendently from the bale band when in position to receive the other end of the loop of the bale band, which end loop is indicated at 6 in Figs. 3, 4 and 5.

The extension 4 constituting part of the entering end bar of the buckle is somewhat longer than the extension 5 constituting the other member of the entering end of the buckle, and these end bars terminate in beveled free ends 7, 8, respectively. In the initial condition the two members 4 and 5 are apart at their free or beveled ends, so that the beveled portions 7 and 8 are laterally separated with respect to the general plane of the buckle. Moreover, the side bars 2 and 3 have the ends remote from the end bar 1 approaching, so that in the initial condition the buckle is narrower at the entering end than at the other end. The result of this is that the beveled ends 7 and 8 overlap, but still are spread apart laterally of the buckle to an extent providing a mouth 9 sufficiently wide to permit the threading of the loop 6 of the band into the buckle, or the threading of the buckle on to the loop 6 of the band.

Customarily a bale band is about one inch in width, and in conformity with such bands the interior of the buckle is about one inch across at its widest point, but is less than one inch across at the entering end, the difference being about one-sixteenth of an inch more or less, and this represents about the extent of extra overlapping of the beveled ends 7 and 8 at the entering end of the buckle. These beveled ends are arranged in facing relation, so that when the members 4 and 5 of the entering end of the buckle are brought together to make the beveled ends 7 and 8 meet, these ends may slide one on the other until the beveled faces come into face contact throughout substantially their whole area. When this occurs the two members 4 and 5 are in substantial alinement, and then the entering end bar made up of the two members 4 and 5 is of substantially the same length as the other end bar 1, the entering end of the buckle having widened in the plane of the buckle sufficiently to make the distance between the side bars at the entering end of the buckle the same as at the other end of the buckle, wherefore the buckle when spread to the extent stated is practically rectangular with the side bars about parallel, instead of approaching toward the entering end, as is the case when the buckle is in its initial condition.

The buckle may have all the inner corners angular, as indicated at 10 in Fig. 1, or the inner corners where the bars 1, 2 and 3 join may be rounded or beveled, as indicated at 11 in Figs. 3, and 4, such corners causing a slight crimping of the sides of the corresponding loop of the bale band when sub-

jected to the expansive force of the bale. This arrangement of the inner corners of the buckle is the only distinguishing feature of the showing of the different figures of drawing.

When the band is applied to the compressed bale the buckle is already fast to one end of the band, and then the other end of the band formed into an appropriate loop is introduced into the buckle through the entering end thereof, the buckle being usually turned sufficiently for the purpose. When the loop of the band has been introduced into the buckle and is brought toward the entering end in embracing relation to the entering end bar made up of the members 4 and 5, the band being somewhat wider than the space between the side bars 2 and 3 at the entering end, the band and buckle are at a slight angle one to the other, as indicated in Fig. 3. Then when the band is put under strain due to the expansive force of the released bale, the buckle is spread in a direction to separate the side bars 2 and 3 and at the same time the members 4 and 5 of the entering end bar of the buckle are caused to approach in a direction perpendicular to the plane of the buckle, so that the beveled faces 7 and 8 seat one against the other with the members 4 and 5 in substantial alinement and imprisoned in the loop 6 of the bale band. The result is that the entering end of the buckle firmly holds the band throughout its entire width with any tendency of the buckle to spread open nullified by the inherent strength of the buckle. This is due to the fact that the buckle is made of heavy gage metal and the strain, being brought upon the full length of the entering end bar with the loop of the band closely encircling the members of the entering end bar, resists the tendency, if present, of a greater spreading apart of the side bars 2 and 3, or of bending of the members 4 and 5 where joining the side bars 2 and 3.

It will be observed that the member 5 is shorter than the member 4, so that the mouth 9 is to one side of the longitudinal center line of the buckle. This is advantageous in facilitating the threading of the loop 6 into the buckle and permitting the full introduction of the loop without so great a turning of the buckle as would be necessary if the mouth 9 were midway of the width of the buckle.

In Figs. 6 and 7 there is shown a buckle substantially the same in size, shape and characteristics as the buckles of Figs. 1 to 5, except that the buckle is made of flat metal. Such structure has certain advantages in that it is more resistant to the pull of the bale band than round wire buckles, and may be readily punched or stamped from sheet metal of suitable gage, which without sacrifice of the efficiency of the

buckle may be somewhat lighter than sheet metal buckles as heretofore made.

Since the buckle of Figs. 6 and 7 corresponds closely to the buckle of Fig. 1 and associated figures, the same reference numerals that are used in Fig. 1 are used, so far as they apply, in Figs. 6 and 7, except that each reference numeral is supplied with the exponent a . In Figs. 6 and 7 the bale band is indicated in dotted lines at 6.

When the second or lower loop of the bale band 6 is introduced into the buckle through the mouth 9 it is necessary to rotate the buckle for a short distance to accommodate the bale band, since the distance between the mouth 9 and the side bar, say, the side bar 2 toward which the loop of the bale band is moved, is less than the width of the bale band. Consequently, in order to get the bale band entirely within the buckle, one side of the loop must be moved toward the corner produced by the junction of the bars 1 and 2 of Fig. 1 and associated figures, or 1^a and 2^a of Fig. 6. The width of the interior of the buckle adjacent to the end bar 1 is about equal to or a small fractional portion of an inch greater than the width of the bale band, while the width of the entering end bar of the buckle between the side bars is or may be a small fractional portion of an inch less than the width of the bale band, although under some circumstances, and especially in the case of the flat metal buckle of Fig. 6, the two members of the entering end bar of the buckle need not actually overlap, although it is preferred that they should initially overlap. When overlapping the two members of the entering end bar of the buckle may spread when the bale band is put under strain, and the buckle is pulled by the expansive force of the bale when released from the compress, so that the two end members of the entering end bar will align with their ends actually or substantially in end to end engagement, so that the same alining effect is obtained as is the case with the beveled ends of the buckle of Fig. 1 and associated figures when the buckle is pulled.

The height of the interior of the buckle of Fig. 6 is less than the width of the buckle, the same as in Fig. 1 and associated figures, so that when the band is introduced into the buckle and one edge of the loop of the band is engaged in the interior corner of the buckle where the end bar 1^a and side bar 2^a join, the other edge of the loop of the band will have entered the buckle beyond the free end of the member 5^a of the entering end of the buckle. However, the buckle cannot then be rotated about the loop of the band to an extent as great as half a revolution, and hence when the expansive force of the bale acts upon the bale band and buckle the introduced loop of the band must necessarily

find lodgment about the entering end bar made up of the members 4^a and 5^a.

Furthermore, the width of the buckle is nowhere greater than approximately the width of the bale band. Ordinarily the interior width of the buckle at the entering end is a small fractional portion of an inch less than the width of the band; that is, considering the band as an inch wide, the buckle at the entering end may have an interior width of about fifteen-sixteenths of an inch. The height of the buckle, that is, the distance between the end bars, is always less than the width of the bale band, although the difference need be only such as to positively prevent the turning of the buckle on the bale band for a half revolution. The interior width of the buckle, that is, the distance between the side bars, never materially exceeds the width of the bale band and is always preferably less than the width of the bale band, especially at the entering end, so that when the band and buckle are subjected to the expansive force of the bale, the bale band will always extend from one side bar of the buckle to the other, and preferably then subjected to forces tending to reduce the width of the bale band, whereby the band is tightly gripped at the edges.

By this arrangement the bale band when under the pull of the bale released from the compress, engages the entering end of the buckle throughout the entire width of the bale band and when the members of the entering end bar overlap, the frictional engagement between the bale band and the buckle is increased to an extent corresponding to the amount of overlapping. This feature aids in preventing rendering of the bale band, prevents tearing or cutting of the bale band which frequently happens where the mouth of the buckle so spreads as to leave a material gap where the bale band is introduced, and liability of pulling out or breaking the buckle is practically avoided.

By making the interior of the buckle of less height than the width of the bale band and of a width at its widest point approximately the same as that of the bale band, and, furthermore, by placing the mouth at the entering end of the buckle to one side of the longitudinal center line of the buckle, the loop of the band may be introduced into the buckle through a mouth represented by laterally spread overlapping members, and the bale band be then positively directed into edge engagement with the opposite side bar from that toward which the band is moving on being introduced into the buckle, so that the band will certainly house the entire length of the entering end bar and engage the latter through substantially the full width of the band, or even to a greater extent than the full width of the band.

What is claimed is:—

1. A bale buckle, comprising a single piece of metal formed into an end bar, two side bars and another end bar, constituting the 5 entering end of the buckle, the last-mentioned end bar consisting of inturned prolongations of the side bars, with said prolongations approaching into initially overlapping spaced relation on opposite sides of 10 the horizontal plane of the buckle, the width of the buckle at the entering end being less than the width of a bale band, whereby when strain is placed upon the bale band, the ends of said prolongations are brought 15 into substantial alinement with each other.
2. A bale buckle, comprising a single piece of metal formed into an end bar, two side bars, and another end bar, constituting the entering end of the buckle, the last mentioned end bar consisting of inturned prolongations of the side bars, with said prolongations approaching into initially overlapping spaced relation on opposite sides of the horizontal plane of the buckle, and 20 25 the overlapping ends where presented toward each other being beveled and arranged in facing relation, the width of the buckle at the entering end being less than the width of a bale band, whereby when strain is placed upon the bale band the ends of said 30 35 prolongations are brought into substantial alinement with each other.
3. A bale buckle, comprising an end bar, two straight side bars permanently joined to the end bar at one of their ends and approaching each other at their other ends, and another end bar consisting of inturned prolongations of the side bars at said other ends and constituting the entering end of 40 45 the buckle, said prolongations approaching into initially overlapping spaced relation on opposite sides of the horizontal plane of the buckle, thereby forming an end bar of less length than the first named end bar and making the entering end of the buckle of less width than a bale band, and said prolongations where overlapping being of reduced width, whereby when strain is placed upon the bale band, the said prolongations are 50 moved into substantial alinement and directly overlapped.
4. A bale buckle comprising a single piece of metal formed into an end bar, two side bars and another end bar constituting the

entering end of the buckle, the second end 55 bar consisting of prolongations of the side bars initially laterally spaced at their free ends, the height of the buckle between the end bars being less than the width of a bale band for which the buckle is designed and 60 the width of the buckle where the prolongations constitute the entering end bar of the buckle being less than the width of a bale band.

5. A bale buckle comprising a single piece 65 of metal forming an end bar, two side bars and another end bar with the second-named end bar constituting the entering end of the buckle, said second end bar consisting of approaching prolongations of the side bars 70 with their free ends laterally spaced, the combined length of the prolongations forming the second end bar substantially equaling the length of the first end bar, the interior height of the buckle being less than the 75 width of the bale band for which the buckle is designed and the interior width of the buckle being at no point greater than the length of the first-named end bar between the side bars. 80

6. A bale buckle comprising a single piece of metal forming an end bar, two side bars and another end bar with the second-named end bar constituting the entering end of the buckle, said second end bar consisting of 85 approaching prolongations of the side bars with their free ends laterally spaced, the combined length of the prolongations forming the second end bar substantially equaling the length of the first end bar, the interior height of the buckle being less than the width of the bale band for which the buckle is designed and the interior width of the buckle being at no point greater than the length of the first-named end bar between 90 95 the side bars, the prolongations forming the entering end bar initially overlapping and the distance between the side bars at the entering end of the buckle being initially less than the width of the bale band. 100

In testimony that I claim the foregoing as my own, I have hereto affixed my signature in the presence of two witnesses.
